ABSTRACT OF THE DISCLOSURE

A system for interconnecting respective electrical conductors of two cables of substantially equal radius, without creating a substantially enlarged section in the cables, includes a plurality of longitudinally spaced connector assemblies. Each connector assembly includes first and second plug members connected to respective groups of conductors and connectable to one another to interconnect the conductors. A first portion of each plug member is defined by an outwardly facing curved surface generated by a radius substantially equal to the radius of the cables. A second portion of each plug member is disposed radially inward with respect to the circumference of the cables to define an area in which remaining electrical conductors of the cables can bypass the connector assembly to the other connector assemblies, without projecting substantially radially outward beyond limits defined by the circumference of the cables. Thus, each connector assembly and its associated bypassing conductors have a combined peripheral configuration substantially corresponding in size and shape to that of the cables. The resulting cable connection is enclosed in a protective covering, such as a heat-shrinkable sleeve.

BACKGROUND OF THE INVENTION

(1) Field of the invention

This invention relates to a multiple connector assembly system for interconnecting strands of cables, and more particularly to a multiple connector assembly system for interconnecting insulated electrical conductors of two communication cables without creating a substantially enlarged section in the cables.

(2) Description of the prior art

In connecting insulated electrical conductors of one communication cable to another communication cable, such as in telephone exchange central offices, it is standard practice to provide a connector plug for each cable, with each plug having terminals connected to respective conductors of its associated cable. The cables then are interconnected by inserting the terminals of one plug into the terminals of the other plug. This arrangement is undesirable, however, because the interconnected plugs produce a section in the joined cables which is enlarged with respect to the remainder of the cables, thereby producing distorted pile-ups when cables are run in side-by-side relationship on cable support racks. The connection also presents a problem when the joined cables must be threaded through an opening, since the opening must be larger than the cables to accommodate the passage of the connector plugs.

Another method of connecting the electrical conductors of the cables is by splicing the conductors, using individual mating connectors for each pair of conductors. Normally, the connections are staggered along the length of the cables in the vicinity of the splice to preclude the formation of a bulge or enlargement of any significant size in the cables. This, however, requires that the con-

2

nections extend a substantial distance along the length of the joined cables, and when the space in which the splice must be accomplished is limited it frequently is not possible to form the connections without creating an enlarged section in the cables. Further, the forming of the splice is time consuming and may be difficult to accomplish because of the inaccessibility of the urea in which the splice is to be located.

SUMMARY OF THE INVENTION

An object of this invention is to provide a new and improved system for interconnecting strands of two cables.

A further object of this invention is to provide a new and improved system for interconnecting strands of two cables without producing a substantially enlarged section in the cables.

Another object of this invention is to provide a new and improved connector assembly for interconnecting strands of two cables without creating a substantially enlarged section in the cables.

In accordance with the invention, each of a plurality of cable connector assemblies, for connecting a respective group of strands in one cable to a corresponding group of strands in another cable, includes first and second connector members connected to respective strands of the cables and connectable to one another to interconnect the strands. A first portion of each connector member is defined by an outwardly facing curved surface generated by a radius substantially equal to the radius

25 of the cables. A second portion of each connector member is disposed radially inward with respect to the circumference of the cables to define an area or open pocket in which remaining strands of the cables are received to bypass the connector assembly to another connector assembly,

30 without projecting substantially radially outward beyond limits defined by the circumference of the cables. Thus, each connector assembly and its associated bypassing strands have a combined peripheral configuration substantially corresponding in size and shape to that of 35 the cables.

40

BRIEF DESCRIPTION OF THE DRAWINGS

FIG. 1 is a side view of a pair of cables having electrical conductors thereof interconnected by a plurality of connector assemblies in accordance with the invention;

45 FIGS. 2a, 2b, 2c and 2d are cross-sectional views taken along the lines 2a—2a, 2b—2b, 2c—2c and 2d—2d, respectively, in FIG. 1, and illustrating relative positions of the connector assemblies and the electrical conductors in the cables;

50 FIG. 3 is a view similar to FIG. 1, showing the connected portions of the cables enclosed in a protective covering;

55 FIG. 4 is an enlarged cross-sectional view of one of the connector assemblies, taken along the line 4—4 of FIG. 1;

FIG. 5 is a cross-sectional view taken along the line 5—5 in FIG. 4 and showing the connector assembly of FIG. 4 in its assembled condition; and

60 FIG. 6 is a view similar to FIG. 5, but showing the connector assembly of FIG. 4 in its disassembled condition.

DETAILED DESCRIPTION

65 Referring to FIG. 1, the disclosed embodiment of the invention relates to a system in which a series of n-longitudinally spaced and axially aligned cable connector assemblies 11 are utilized to interconnect insulated electrical conductors C1—C100 of a first cable 12 to corresponding insulated electrical conductors C1'—C100' of a second cable 13, the cables being of substantially equal

radius and the designation n representing the number of connector assemblies required. In the disclosed embodiment of the invention, four of the cable connector assemblies $11a$, b , c and d are shown for this purpose, the connector assemblies being of special construction so as to accomplish the interconnection of the cables 12 and 13 without creating any substantial enlargement therein, and having relative positions circumferentially of the cables as illustrated in FIGS. 2a, 2b, 2c and 2d, respectively.

Since all of the connector assemblies $11a$, b , c and d are of identical construction, only one will be described in detail. As is best shown in FIG. 6, the connector assembly $11a$ includes a set of mating connector plugs 14 and 16 . The connector plug 14 includes a plurality of socket-type terminals 17 connected to respective ones of the electrical conductors $C1-C25$ of the first cable 12 and the connector plug 16 includes a plurality of plug-in type terminals 18 connected to respective ones of the electrical conductors $C1'-C25'$ of the second cable 13 . When the connector plugs 14 and 16 are assembled to each other as shown in FIG. 5, the plug-in terminals 18 are received in the socket type terminals 17 to interconnect the conductors $C1-C25$ and $C1'-C25'$ electrically in a well known manner. The remainder of the conductors $C26-C100$, which are not connected to the connector assembly $11a$, bypass the connector assembly to the other connector assemblies $11b$, c and d .

Referring to FIG. 4, the construction of the connector assembly $11a$ is such that the connector assembly and its associated bypassing conductors $C26-C100$ do not create any substantial enlargement in the cables 12 and 13 . In this regard, the connector plug 14 includes an outwardly facing curved surface $14a$ having a radius substantially equal to the radius of the cables 12 and 13 , and also includes peripheral surface portions $14b$ which are disposed radially inward with respect to the periphery of the cables to provide an area or open pocket for receiving the conductors $C26-C100$. Similarly, the connector plug 16 of the connector assembly $11a$ includes an outwardly facing curved surface $16a$ in alignment with the surface $14a$ of the connector plug 14 and having a radius substantially equal to the radius of the cables 12 and 13 . The connector plug 16 also includes peripheral surface portions $16b$ in alignment with the surfaces $14b$ of the connector plug 14 and disposed radially inward with respect to the periphery of the cables 12 and 13 . When the connector plugs 14 and 16 are assembled as shown in FIG. 5, the curved surfaces $14a$, $16a$ are substantially in alignment with the peripheries of the two cables 12 and 13 , and the inwardly disposed surface portions $14b$, $16b$ provide an area or open pocket in which the electrical conductors $C26-C100$ (FIG. 4) are received to bypass the connector assembly $11a$ externally thereof without projecting substantially radially outward beyond the peripheral limits of the cables (represented by the broken line in FIG. 4). Thus, the connector assembly $11a$ and the bypassing electrical conductors $C26-C100$ have a combined peripheral configuration substantially corresponding to the size and shape of the cables 12 and 13 , and the portion of the connected cables in the vicinity of the connector assembly is not substantially enlarged relative to the remainder of the cables.

Each of the connector plugs 14 and 16 of the connector assembly $11a$, with their associated terminals 17 and 18 mounted therein, may be formed in any suitable manner. For example, prestripped end portions of the insulated electrical conductors $C1-C25$ associated with the connector plug 14 may be inserted in the terminals 17 and secured therein by crimping and/or soldering. The body of the connector plug 14 then can be molded about the terminals to form the connector plug construction shown in FIG. 6. In the alternative, the body of the connector plug 14 may be premolded and provided with suitable apertures for receiving the terminals 17 . Then, after the prestripped electrical conductors $C1-C25$ have been inserted and secured in the terminals 17 , the terminals can

be press-fitted or otherwise suitably secured in the apertures.

At the second connector assembly $11b$ (FIG. 2b), electrical conductors $C26-C50$ of the first cable 12 are connected to its connector plug 14 and the conductors $C26'-C50'$ of the second cable 13 are connected to its connector plug 16 . The conductors $C51-C100$ of the first cable 12 , however, again bypass the second cable connector assembly $11b$ to the third and fourth cable connector assemblies $11c$ and $11d$. In addition, the conductors $C1'-C25'$ bypass the second cable connector assembly $11b$ in the reverse direction to the first cable connector assembly $11a$.

Similarly, referring to FIG. 2c, conductors $C51-C75$ of the first cable 12 and conductors $C51'-C75'$ of the second cable 13 are interconnected by the plugs 14 and 16 of the third cable connector assembly $11c$, with conductors $C76-100$ bypassing the third connector assembly to the fourth connector assembly $11d$, and with conductors $C1'-C50'$ bypassing the third connector assembly in the reverse direction to the first and second connector assemblies $11a$ and $11b$. The arrangement at the fourth connector assembly $11d$ (FIG. 2d) is the same as at the first connector assembly $11a$, with the conductors $C76-C100$ and $C76'-C100'$ being interconnected by the plugs 14 and 16 of the fourth connector assembly, and with conductors $C1'-C75'$ of the second cable 13 bypassing this connector assembly to the first, second and third connector assemblies $11a$, b and c .

After the connector plugs 14 and 16 of the connector assemblies $11a$, b , c and d have been interconnected as shown in FIG. 1, a suitable protective covering 19 , such as a heat shrinkable sleeve member, may be applied to the resultant cable connection, as illustrated in FIG. 3. In this regard, the sleeve member 19 may be prepositioned over one of the cables 12 or 13 prior to their being connected, and after they have been connected the sleeve member may be slid longitudinally along the cable over the connected area. Then, by the application of suitable heat to the sleeve 19 it may be caused to shrink about the electrical conductors $C1-C100$ and $C1'-C100'$ and the cable connector assemblies $11a$, b , c and d in tight-fitting relationship.

Summarizing, a system has been disclosed whereby respective ones of the electrical conductors $C1-C100$ and $C1'-C100'$ of the cables 12 and 13 can be interconnected without creating a substantially enlarged section in the cables. The system includes four longitudinally spaced cable connector assemblies $11a$, $11b$, $11c$ and $11d$, each including first and second plug members 14 and 16 for interconnecting respective groups of the conductors $C1-C100$ and $C1'-C100'$. First portions of the plug members 14 and 16 are defined by outwardly facing curved surfaces $14a$ and $16a$, respectively, generated by a radius substantially equal to the radius of the cables 12 and 13 . Second portions $14b$ and $16b$ of the plug members 14 and 16 , respectively, of each connector assembly 11 , are disposed radially inward with respect to the circumference of the cables 12 and 13 to define an area in which respective ones of the conductors $C1-C100$ and $C1'-C100'$ can bypass the plug members to the other connector assemblies, without projecting substantially radially outward beyond limits defined by the circumference of the cables 12 and 13 . The resulting cable connection is enclosed in the protective sleeve 19 .

What is claimed is:

1. A system for connecting strands in a first cable to respective strands in a second cable, wherein the cables are of substantially equal radius, which comprises:
at least two longitudinally spaced connector assemblies of non-circular configuration displaced circumferentially with respect to one another and each having first and second connector members, the connector members of each connector assembly being connected to respective groups of the strands in the cables and

connectable to one another to interconnect the strands;
first portions of the connector members of each connector assembly being defined by outwardly facing curved surfaces generated by a radius substantially equal to the radius of the cables so that the curved surfaces substantially correspond to the peripheral configuration of adjacent portions of the cables when the connector members are interconnected and substantially form a longitudinally extending continuation of the peripheral configuration of the adjacent portions of the cables; and
second portions of the connector members of each connector assembly being defined by peripheral surface portions disposed radially inward with respect to the circumference of the cables to define a space in which remaining strands of the cables can bypass said connector assembly externally thereof to another of said connector assemblies without projecting substantially radially outward beyond limits defined by the circumference of the cables, whereby each connector assembly and its associated remaining strands have a combined peripheral configuration substantially corresponding in size and shape to that of the cables.

2. A connector assembly for connecting one of a plurality of groups of strands in a first cable to one of a plurality of groups of respective strands in a second cable, wherein the cables are of substantially equal radius, which comprises:

first and second connector members of non-circular configuration connected to respective strands of the cables and connectable to one another to interconnect the strands;
a first portion of each of said connector members being defined by an outwardly facing curved surface generated by a radius substantially equal to the radius of the cables so that the curved surfaces of said connector members substantially correspond to the peripheral configuration of adjacent portions of the cables when the connector members are interconnected and substantially form a longitudinally extending continuation of the peripheral configuration of the adjacent portions of the cables; and
a second portion of each of said connector members being defined by a peripheral surface portion disposed radially inward with respect to the circumference of the cables to define a space in which remaining strands of the cables can bypass the connector assembly externally thereof without projecting substantially radially outward beyond limits defined by the circumference of the cables, whereby the connector assembly and the remaining strands have a combined peripheral configuration substantially corresponding in size and shape to that of the cables.

3. An electrical connector assembly for connecting one of a plurality of groups of insulated conductors in a first cable to one of a plurality of groups of respective insulated conductors in a second cable, wherein the cables are of substantially equal radius, which comprises:

first and second connector members of non-circular configuration and each having a plurality of terminals connected to respective insulated conductors of the cables and connectable to one another to interconnect the insulated conductors;
a first portion of each of said connector members being defined by an outwardly facing curved surface generated by a radius substantially equal to the radius of the cables so that the curved surfaces of said connector members substantially correspond to the

peripheral configuration of adjacent portions of the cables when the terminals of the connector members are interconnected and substantially form a longitudinally extending continuation of the peripheral configuration of the adjacent portions of the cables;

a second portion of each of said connector members being defined by a peripheral surface portion disposed radially inward with respect to the circumference of the cables to define a space in which remaining insulated conductors of the cables can bypass the connector assembly externally thereof without projecting substantially radially outward beyond limits defined by the circumference of the cables, whereby the connector assembly and the remaining insulated conductors have a combined peripheral configuration substantially corresponding in size and shape to that of the cables.

4. In an arrangement for connecting together two multi-strand cables wherein the strands of the cables are arranged in a circular bundle;

a series of n -longitudinally spaced and axially aligned connector assemblies, each succeeding assembly being displaced equidistantly about the center of the cables, where n is the number of said connector assemblies;

each connector assembly having means for receiving and connecting substantially $1/n$ of the strands and each assembly having arcuate peripheral surface portions which in conjunction with the other longitudinally spaced arcuate peripheral surface portions of said other assemblies define a complete circle having a diameter which is substantially equal to the diameter of the circular bundle of strands;

each of said connector assemblies being shaped to also have a second peripheral surface portion recessed with respect to the circular bundle of strands to provide an open pocket for receiving substantially

$$\frac{n-1}{n}$$

of the strands and bypassing the strands to said other connector assemblies, each of said connector assemblies and the strands received in its associated pocket having a peripheral size which is substantially equal to the peripheral size of the circular bundle of strands.

5. An arrangement as defined in claim 4, wherein each connector assembly has substantially $1/n$ plug-in type terminals and associated socket-type terminals for interconnecting the strands received within said connector assembly.
